UNITED STATES PATENT OFFICE.

FREDERICK C. KROEGER, OF ANDERSON, INDIANA, ASSIGNOR, BY MESNE ASSIGNMENTS, TO DELCO-REMY CORPORATION, OF DAYTON, OHIO, A CORPORATION OF DELAWARE.

ENGINE-STARTING APPARATUS.

Application filed May 6, 1924. Serial No. 711,393.

This invention relates to starting apparatus for internal combustion engines, particularly, to a type of apparatus including an electric motor operating a gear which is 6 movable axially into engagement with a gear connected with the engine such as the engine flywheel gear.

Among the objects of the invention are the connecting of the motor gear with the engine gear and the operating the motor by 10 manual operation; for example, by means of a starting lever, and the demeshing of the motor gear from the engine gear automatically when the engine starts, regardless of 15 whether the starting lever is still maintained in engine-starting position.

In order to accomplish these objects the invention provides means responsive to the self-operativeness of the engine, such as 20 electrical means, rendered operative by the operation of the engine, for disconnecting the starting motor pedal from a device which engages the motor gear to shift it axially into engagement with the flywheel 25 gear. The motor gear is connected with the motor shaft by a spiral spline or screw thread. Consequently, when the engine becomes self-operative, the motor gear will be automatically demeshed from the engine 30 gear, altho the starting motor pedal may not yet be released by the operator.

Further objects and advantages of the present invention will be apparent from the following description, reference being made 35 to the accompanying drawings, wherein a preferred form of embodiment of the present invention is clearly shown.

In the drawings:

Fig. 1 is a fragmentary side view partly 40 in section, of a starting motor and gearing, including a form of the invention, the apparatus being in normal or inoperative condition.

Fig. 2 is a sectional view on the line 2—2 45 of Fig. 1.

Fig. 3 is a wiring diagram, showing one form of the electrical circuit including the present invention.

Fig. 4 is a view similar to Fig. 1, showing 50 the apparatus in condition for cranking the engine; and

Fig. 5 is a view similar to Fig. 4, showing the operating lever in position to close the motor switch, and showing the operation of

an electro-magnet connected in the motor 55 circuit, to disconnect the operating lever from the motor gear so that the motor gear may be automatically demeshed, as indicated in dotted lines in this figure.

Referring to the drawings: 20 designates 60 a gear housing including a bracket 21 for supporting the housing upon the frame of an engine, not shown, but represented in the drawings by an engine flywheel gear 22. The housing 20 supports a motor field frame 23. By means of a bearing (not shown), the frame 23 supports the motor shaft 24 having one end journalled at 25 in the gear housing 20. The shaft 24 is provided with a spirally-splined or threaded portion 26, 70 which engages an internally-threaded motor gear 27 carrying a flanged washer 28 projecting beyond the periphery of the gear.

The motion-transmitting device for shifting gear 27 endwise into engagement with the 75 gear 22 includes a bifurcated lever 29, pivoted upon a shaft 30 carried by housing 20, the bifurcations of lever 29 being connected by a yoke 31 and the ends thereof being rounded at 32 to engage a grooved collar 33. Between collar 33 and the end 34 of the 80 armature core there is located a spacer 35. A spring 36, coiled around the shaft 30 has one end 37 bearing against the gear housing 20, and the other end 38 bearing against the 85 yoke 31. Between the grooved collar 33 and the gear 27 there is located a spring 40 in an initial state of compression by means of 90 spring housing members 41 and 42, which limit the separation of members 33 and 27. Housing member 41 is attached as shown in Fig. 1 to the collar 33 and is provided with a flange 43 connected with a flange 45 of the member 42 by lugs 44 integral with flange 45 and bent around flange 43. Member 42 95 is provided with an opening 46, which is large enough to clear the motor gear 27 but is smaller in diameter than the external diameter of the washer 28.

The manually operable means for moving 100 the motion-transmitting device, includes a lever 50 pivoted upon the shaft 30 and carrying an adjustable screw 51 adapted to engage the plunger 52 of a motor-operating switch enclosed within a housing 53. One 105 terminal of the switch for connection with a current source is shown at 54 and the other terminal not shown is connected with the

motor field circuit. The lever 50 is operated by a rod 55 carrying a pedal 56 located in convenient reach of the driver.

The means for connecting the lever 50 with a gear shifting lever 29, includes a pawl 60 pivoted upon a stud 61 carried by lever 50. The pawl engages a notch 62 in the lever 29 and is normally held in this position by means of a spring 63 coiled around the stud 61 and having one end 64 bearing against an ear 65 of the pawl 60, said ear being at right angles to the main portion of the pawl 60. The other end 66 of spring 63 bears against a stud 67 on lever 50.

15 The motor field frame 23 supports an electro-magnet 70 of the solenoid type which, when energized, will actuate an armature on plunger 71 from the position shown in Figs. 1 and 4, into the position shown in Fig. 5. The plunger 71 includes a head portion 72 carrying a screw 73 adapted to engage the ear 65 of the pawl 60.

In the diagram shown in Fig. 3, 80 indicates a storage battery or other source of current, grounded at 81 and connected by a switch 82 with the electric starting motor, which includes a field winding 83 and an armature 84, which is grounded at 85. The electro-magnet 70 is connected in parallel

30 with the armature 84 and is grounded at 86.

A collar 90 is attached to the motor shaft 24 and a thrust washer 91 is located between the collar 90 and a plane surface 92 formed on the housing 20.

35 The manner of operating the invention is as follows:

When the engine is at rest the starting apparatus is normally in the position shown in Fig. 1. To start the engine a pedal 56 is depressed causing the lever 50 to move into the position shown in Fig. 4 to effect the movement of the lever 29 and the closing of the motor switch by depressing the plunger 52 to the position shown in Fig. 4. In case 40 the teeth of the gear 27 register with the tooth spaces of the gear 22, the engagement of these gears will take place before the motor switch is closed. But in case of tooth abutment the spring 40 will be compressed 45 beyond its initial state of compression, thus permitting the motor switch to be closed. The motor will then turn to register the gear 27 for enmeshment with the gear 22, and slight rotation of gear 27 will release the spring 40 which will quickly jump the gear 50 into engagement with the gear 22. After the gear 27 has been moved endwise along the shaft until it engages the collar 90, the gear 27 will turn with the shaft 24 to operate the engine gear 22. This engine-crank- 55 ing position of gear 27 is shown in Fig. 4.

Movement of lever 50 into the position shown in Fig. 4, brings the ear 65 of pawl 60 closely adjacent the screw 73 carried by the magnet plunger 71. While the motor is

cranking the engine, pressure between the pawl 60 and the notch 62 of lever 29 is relieved, as indicated in Fig. 4, so that the magnet 70 has but the force exerted by spring 63 to overcome in shifting the pawl 60 from the position shown in Fig. 4 to the position shown in Fig. 5. When the engine becomes self-operative and drives the motor as a generator, the counter-electromotive force developed by the motor armature 84 will energize the magnet 70 sufficiently to move the plunger 71 into the position shown in Fig. 5. The motor gear 27 is now released from the starting pedal 56, therefore, the engine will automatically demesh the motor gear 27 from the engine gear 22, and cause the collar 33 and the lever 29 to return to the positions indicated in dash lines in Fig. 5. Therefore, it is apparent that the motor gear 27 will be automatically demeshed, regardless of whether the operating lever 50 is held down after the engine becomes self-operative.

The demeshing of the gear 27 is assisted by spring 36 which maintains the gear shifting mechanism in position shown in Fig. 1. The spacer 35 limits the endwise movement of the collar 33 to the left as viewed in Fig. 3.

To stop the motor, the operator releases the pedal 56. A spring 56^a located between the pedal and the stationary part such as the floor board 56^b of the vehicle, causes the lever 50 to return to the position shown in Fig. 1. A slight clearance between the pawl 60 and lever 29 is provided in the normal "at rest" position of the apparatus, so that the pawl 60 will then enter the notch 63.

It is apparent, therefore, that the starting apparatus will not be damaged by failure to release the pedal 56 as soon as the engine starts. Automatic demeshment of gear 27 will take place regardless of the status of the starting pedal 56. Therefore, the present invention avoids the use of an overrunning clutch connecting the motor armature with starting gears in order to protect the armature against excessive rotation when the engine starts.

While the form of embodiment of the present invention as herein disclosed, constitutes a preferred form, it is to be understood that other forms might be adopted, all coming within the scope of the claims which follow.

What I claim is as follows:

1. Engine starting apparatus comprising, in combination, an electric motor; means for connecting the motor with a gear of the engine to be started including a gear movable into mesh with said engine gear and including devices whereby the motor gear is automatically demeshed from the engine gear when the engine starts; a motor switch; a pedal-operated member for operating the

motor switch; means for transmitting motion from said pedal member to the motor gear including disconnectible parts and including a spring which yields to permit the

electromagnetic means responsive to the operation of the engine for moving the latch to disconnect the pedal lever from the motor gear.

50

5 pedal member to close the switch in case the motor gear teeth abut the engine gear teeth; and electrical means responsive to self-operation of the engine for causing said parts to become disconnected, whereby the motor gear will be demeshed when the engine starts regardless of manipulation of the pedal member.

10 2. Engine starting apparatus comprising, in combination, an electric motor; means for connecting the motor with a gear of the engine to be started including a gear movable into mesh with said engine gear and including devices whereby the motor gear is automatically demeshed from the engine gear when the engine starts; a motor switch; a pedal-operated lever for operating the motor switch; a latch pawl pivoted on said pedal lever; a member operated by said latch pawl; a spring transmitting motion from said member to the gear to permit the lever to close the switch in case the motor gear teeth abut the engine gear teeth; a magnetizable member movable to disconnect the latch from the gear-moving member; and an electromagnet energized in response to engine operation for actuating the magnetizable member.

15 3. Engine starting apparatus comprising, in combination, an electric motor; a spirally-splined shaft driven by the motor; a gear threaded on said splined shaft and movable endwise into mesh with the gear of an engine to be started; a motor switch; a pedal-operated lever for actuating the switch; means for transmitting motion from the pedal lever to the motor gear including a spring which yields to permit closing the motor switch in case the teeth of the motor gear abut the teeth of the engine gear, and including disconnectible parts one of which is a latch pawl pivoted on the pedal lever; and

4. Engine starting apparatus comprising, in combination, an electric motor; a spirally-splined shaft driven by the motor; a gear threaded on said splined shaft and movable endwise into mesh with the gear of an engine to be started; a frame enclosing motor parts and the shaft and gear; a pedal-operated lever and a gear shifting lever coaxially pivoted on said frame; a latch pivoted on the pedal lever and engaging the gear-shifting lever; an electro-magnetic device mounted on the frame and having an armature located in the path of motion of the latch in order to engage the latch to disconnect the same from the gear-shifting lever when the magnet is energized; and a switch mounted on the frame and having an operating member located in the path of movement of the pedal lever.

65

20 5. Engine starting apparatus comprising, in combination, an electric motor; a spirally-splined shaft driven by the motor; a gear threaded on said splined shaft and movable endwise into mesh with the gear of an engine to be started; means for moving the motor gear endwise into mesh with the engine gear including a pedal-operated member, a gear-shifting member and a latch pivoted thereon and movable out of engagement with the gear-shifting member; a motor switch operated directly by the pedal member the latch connection permitting the pedal member to be released and the switch to open in case the engine should fail to start after gears are meshed; and electromagnetic means responsive to engine operation for moving the latch to disconnect the pedal member from the gear-shifting member.
